UNITED STATES PATENT OFFICE

WALTER WOLFF, OF CHICAGO, ILLINOIS, ASSIGNOR OF ONE-FIFTH TO ROBERT H.
WENDT, OF CHICAGO, ILLINOIS

DESIGN FOR A GARMENT SUPPORT

Application filed January 14, 1929. Serial No. 29,596. Term of patent 3½ years.

To all whom it may concern:

Be it known that I, WALTER WOLFF, a citizen of the United States, residing at Chicago, in the county of Cook and State of Illinois, have invented a new, original, and ornamental Design for Garment Supports, of which the following is a specification, reference being had to the accompanying drawings, forming a part thereof.

Referring to the drawings:

The figure is a perspective view of the garment support showing my new design.

I claim:

The ornamental design for a garment support, as shown.

In witness whereof, I hereunto subscribe my name, this 11th day of January, 1929.

WALTER WOLFF.
